Primary Examiner — Rosemary K Tarcza*Assistant Examiner* — Christy M Nemeth(74) *Attorney, Agent, or Firm* — Mintz Levin Cohn Ferris Glovsky and Popeo, P.C.(57) **CLAIM**

The ornamental design for a portable power supply, as shown and described.

DESCRIPTION

FIG. 1 is a top, left side perspective view of a portable power supply of my new design; and,

FIG. 2 is top, right side perspective view thereof.

The broken lines in the drawings are for the purpose of illustrating portions of the portable power supply that form no part of the claimed design.

1 Claim, 2 Drawing Sheets(56)
